UNITED STATES PATENT OFFICE

142,512

DESIGN FOR A COMBINATION CHILD'S CART AND ROCKER

Alfred J. Cronk, Chicago, Ill.

Application December 8, 1944, Serial No. 116,795

Term of patent 3½ years

(Cl. D34—15)

To all whom it may concern:

Be it known that I, Alfred J. Cronk, a citizen of the United States, residing at Chicago, in the county of Cook and State of Illinois, have invented a new, original, and ornamental Design for a Combination Child's Cart and Rocker, of which the following is a specification, reference being had to the accompanying drawing, forming a part thereof:

In the drawing:

Fig. 1 is a perspective view of a combination

child's cart and rocker, showing my new design;

Fig. 2 is a perspective view thereof with the rocker member removed and showing the device as it appears when used as a cart; and

Fig. 3 is a perspective view of the rocker member.

I claim:

The ornamental design for a combination child's cart and rocker, substantially as shown and described.

ALFRED J. CRONK.
